UNITED STATES PATENT OFFICE.

ARA D. CROCKER, OF SHEBOYGAN, WISCONSIN, ASSIGNOR TO THE CROCKER CHAIR COMPANY, OF SAME PLACE.

DESIGN FOR A CHAIR OR STOOL.

SPECIFICATION forming part of Design No. 29,396, dated September 20, 1898.

Application filed August 25, 1898. Serial No. 689,527. Term of patent 7 years.

To all whom it may concern:

Be it known that I, ARA D. CROCKER, a citizen of the United States, residing at Sheboygan, in the county of Sheboygan and State of Wisconsin, have invented and produced a new and original Design for Chairs or Stools; and I do hereby declare the following to be a full, clear, and exact description of the same, reference being had to the accompanying drawings, forming a part thereof.

In the said drawings, Figure 1 is a view in front or rear elevation, and Fig. 2 a view in end elevation, of a chair or stool embodying my new design.

My design relates to the new and original shape or configuration of the article.

The leading or essential feature consists in the unitary design for a chair or stool made the subject of illustration, comprising four legs the upper ends of which are vertical and the lower ends of which are curved so as to flare outwardly, and which legs are connected together by series of horizontally-disposed rounds or braces, in connection with the shape of the seat of the chair, which has parallel straight sides curved on the arc of a circle, with the concave side uppermost between the lines of the legs, beyond which the said seat is curved at each end in the opposite direction, or with the convex side uppermost, on the arcs of smaller circles, while the said ends (which are of less width than the length of the sides of the said seat) are formed on the lines of a double ogee at each side, with the central portion on the line of the arc of a circle connecting the ends of the adjacent or inner ogees, the said seat resting upon the upper ends of the legs, the tops of which are beveled from the outer to the inner side on curved lines corresponding to the

curve of the seat, while on the upper surface of the said seat, just above the line of said legs, there appear rounded bosses of a shape like that of a small exterior section cut from a sphere.

The rounds or braces which connect each leg of the chair or seat with its adjacent leg are arranged in pairs, one above and in vertical line with the other and parallel therewith, and each brace intermediate of its ends is formed with a series of circumferential rounded portions separated by narrow rounded rings, and exterior to the outer rings are annular grooves, from which points the said rounds or braces are gradually tapered toward their ends where they come in contact with the legs. Above the line of the upper braces each leg is formed with a circumferential groove, and above that with a pair of concave rounded portions separated by another annular groove, and the lower one of said rounded concave portions being formed with a centrally-disposed pair of circumferential rings, while above the upper one of said rounded concave portions the top of the leg is formed cylindrical up to the point where it is beveled off to coincide with the under surface of the seat.

Having thus described my invention, what I claim as new, and desire to secure by Letters Patent, is—

The design for a chair or stool, substantially as herein shown and described.

In testimony whereof I affix my signature in presence of two witnesses.

ARA D. CROCKER.
